(57) **CLAIM**

The ornamental design for a metal sheet material for vehicle panel.

DESCRIPTION

FIG. 1 is a perspective view of a metal sheet material for vehicle panel according to the present design;
 FIG. 2 is a front elevation view thereof;
 FIG. 3 is a rear elevation view thereof;
 FIG. 4 is a right elevation side view thereof;
 FIG. 5 is a left elevation side view thereof;
 FIG. 6 is a top plan view thereof;
 FIG. 7 is a bottom plan view thereof;
 FIG. 8 is an enlarged view of the circumscribed area shown in FIG. 6;
 FIG. 9 is a cross-sectional view of the design shown along the line 9-9 in FIG. 8; and,
 FIG. 10 is a cross-sectional view of the design shown along the line 10-10 in FIG. 8.

1 Claim, 7 Drawing Sheets
